3 Claims. (Cl. 179—108)

ABSTRACT OF THE DISCLOSURE

A modulated flow acoustic device is provided wherein the flow of a combustible gas is modulated in accordance with signal information. The modulated gas stream is burned whereby sonic energy is produced at a higher sound intensity than is obtainable in the absence of combustion.

This invention relates to modulated gas flow loudspeakers, and more particularly to a method and means for increasing the acoustical output thereof.

A modulated gas flow loudspeaker is a device which accepts a steady flow of gas and modulates the gas flow rate (increases and decreases) in a manner continuously responsive to a control signal. The gas flow variations produce an acoustical output.

In order to increase the acoustical output of a modulated flow acoustic device, one increases the magnitude of the gas flow rate or the control signal. However, for any given device, electrical and mechanical considerations limit the output which one can obtain by increasing the gas flow and control signal inputs.

An object of this invention is to provide an arrangement whereby acoustical output of any given modulated flow acoustic device can be increased without increasing the gas flow rate or control signal.

Yet another object of the present invention is the provision of a novel and improved construction for a loudspeaker whereby its acoustical output is increased extensively over that heretofore obtainable with a given loudspeaker construction.

A further object of the present invention is the provision of a novel and improved construction for a siren whereby its acoustical output is increased extensively over that heretofore obtainable with a given siren construction.

The foregoing and other objects of this invention may be achieved in a construction for a modulated flow acoustic device whereby flow of a combustible gas is modulated in accordance with the signal information. After modulation, the gas stream is burned. This adds energy from the combustion to the sonic energy to produce a higher sound intensity than would be obtained in the absence of combustion.

The novel features that are considered characteristic of this invention are set forth with particularity in the appended claims. The invention itself both as to its organization and method of operation, as well as additional objects and advantages thereof, will best be understood from the following description when read in connection with the accompanying drawings, in which:

FIGURE 1 is a cross-sectional view of a loudspeaker structure which is modified in accordance with this invention;

FIGURE 2 is a cross-sectional view of another embodiment of the invention; and

FIGURE 3 is a view in cross-section of a modulated flow acoustic device, such as a siren, modified in accordance with this invention.

Reference is now made to FIGURE 1 which comprises a cross-sectional view of a loudspeaker construction in accordance with this invention. A typical loudspeaker 10, which may be of the electrodynamic type, is mounted in

2

the usual rear closure 12, in a manner well known in the art. The rear closure 12 is preferably made of metal. An opening is provided therein so that leads 14 may extend from a signal source 16 which provides signals for driving the loudspeaker to be connected to the voice coil 18 of the loudspeaker. A closure member 20 is provided for the closure 12. The closure member 20 is attached to the rear closure 12 as by bolts 22.

The portion of the rear surface 24 which is opposite to the diaphragm 26 of the loudspeaker is given the shape of a frustum of a cone so that it substantially parallels the diaphragm, and also is spaced therefrom. The center of the cover member 20 has an opening 27 therein which has the shape of two truncated cones intersecting at their smaller ends in a small straight section 28, with the smaller cone being on the side adjacent the base of the diaphragm 26 and the larger side opening out of the cover 20. A metal screen 30 is placed in the opening 29 adjacent the outside edge. A passageway 32 is provided in the closure member 20 which couples the space between the diaphragm and the back side of the closure 20 to the outside of the container. The source of combustible gas 34 is connected by means of a pipe or hose 36 to the outside end of the opening 32. A valve 38 which is adjustable, controls the flow of gas from the source of combustible gas through the passage 32 into the space between the rear surface 24 and the diaphragm 26.

In operation, the signal source 16 provides electrical signals which drive the loudspeaker 10. Gas from the source 34 is enabled to flow in the space provided adjacent the diaphragm so that it may be modulated by the vibrations of the diaphragm in response to the signal source. The vibration of the diaphragm varies the cross-section of the space between it and the rear surface 24 in accordance with its motion thus producing a varying flow resistance to the gas which in turn produces variations in the flow of the gas which passes through the opening 28. The gas is ignited after it passes through the opening 28 to produce a flame 40. The flame is supported by the wire mesh 30.

It is observed that when the flame is ignited there is a thermal augmentation of the acoustic output of the loudspeaker. The amount of augmentation may be optimized by adjustment of the flow rate of the combustible gas using the valve 38. In an embodiment of the invention which was built and successfully operated, a mixture of air and natural gas was employed as the combustible gas. It was found that not only the flow rate adjustment, but also the air to gas ratio of the mixture affected the extent of the augmentation of the acoustic output. These adjustments may easily be monitored by using a microphone appropriately located in front of the loudspeaker, the output from the microphone being applied to a voltmeter or sound level meter. In the embodiment of the invention which was built, when the optimum adjustment was obtained, the measured sound pressure level was more than 10 db higher than with no combustion but otherwise identical conditions.

FIGURE 2 illustrates in cross-section another embodiment of this invention whereby a loudspeaker operating along the same principles as the one shown in FIGURE 1 is loaded by an acoustic horn 42. In this embodiment of the invention, there is provided the conventional magnet 44 having a circular slot therein within which the voice coil 46 is placed and supported by a voice coil support 48. The voice coil 46 is actually wound on a bobbin 50 which is attached to the voice coil support 48. The voice coil is driven by signals received from a signal source 52.

The magnet 44, voice coil and support are placed within a container 54 having a top wall 54A, the inner side

3

of which is spaced from the top of the loudspeaker to form a passageway 56 therewith. An opening is placed in the center of the top wall 54A. A gas flow smoothing member 58 is placed on the top of the magnet 44 concentrically with the voice coil 46. The gas flow smoothing member has side walls which are substantially parallel and almost coextensive with the bobbin. Then the walls curve inwardly in a generally conical manner to a point. The walls of the opening in the top wall 54A curve in a somewhat parallel manner with the walls of the gas flow smoothing member to define an exit passageway 60 therebetween. The area of this passageway, taken perpendicular to the gas flow, varies with distance along it in substantially the same manner as the law of expansion of the horn 42.

The horn 42 is placed on the top wall 54A with the opening in its throat matching that of the exit passageway 60. An inlet opening 62 in the side wall of the container 54 admits a combustible gas into the passageway 56. The signal source provides signals to the voice coil which together with the bobbin 50 respond thereto by moving more or less into and out of the passageway 56. Thereby, the gas flow through the passageway is modulated by the signals from the signal source 52. The flame holding screen 64 may be advantageously located within the small cross-section portion of the horn by controlling gas flow rate and mixture ratio. As a general principle, at this location the flame velocity will approximately equal the rate of gas outflow.

The horn serves the function of increasing the efficiency and directivity of radiation.

FIGURE 3 shows in cross-section another embodiment of this invention wherein a conventional siren 70 is employed. Gas, instead of air, is fed from a source of combustible gas 72 into an opening in the case 74 of the siren 70. The gas flow is modulated by the rotating chopper wheel 76 which is within the case. The rotating chopper wheel is driven from an external drive source, represented here by a drive shaft 78. The modulated gas is urged by the rotating chopper wheel toward an outlet opening 80 in the case, over which is placed the acoustic horn 82 containing the flame supporting screen 86. The acoustic output of the modified siren is increased considerably when the gas is ignited and burned.

Other arrangements of this invention may be provided wherein fuel and oxidant gases are kept separate and the flow of only one component is modulated. Mixture can take place after modulation, but before ignition. This may be done in any of the structures shown in FIGURES 1, 2 or 3 by feeding one of the gases into the region between the throat of the acoustic horn and below the flame supporting screen by means of a pipe connection to a source of supply.

Because combustible gases are used, the thermoacoustic loudspeaker must employ safety devices to stop gas flow if the flame goes out. Flashback prevention and ignition means must also be provided. Such devices are well known in the combustion art.

There has accordingly been shown herein a novel and useful method and means of increasing the output of an acoustic device by using it to modulate a combustible gas which is then ignited.

What is claimed is:

1. The improvement in a loudspeaker of the type having a diaphragm which is actuated responsive to signals to modulate the air surrounding said diaphragm comprising a closure member spaced from said diaphragm to define a chamber therebetween, a source of combustible gas, an opening at one edge of said closure member extending between said chamber and its outside edge, a source of combustible gas, means for introducing combustible gas through said opening into said chamber, a second opening in said closure member extending outward from the region of said closure member in said chamber over the center of said diaphragm, a flame holding screen disposed in said second opening near the outside edge of said closure member, whereby when said combustible gas passing through said flame holding screen is ignited the acoustic output of said loudspeaker is increased.
2. A thermoacoustic loudspeaker comprising a diaphragm, means to actuate said diaphragm responsive to signals for modulating the air surrounding said diaphragm in accordance with said signals, means forming an enclosure with said diaphragm, said enclosure forming means having walls spaced opposite from and substantially parallel to said diaphragm, a source of combustible gas, means for introducing combustible gas from said source into said enclosure, a gas escape opening in said enclosure forming means positioned over the center of said diaphragm, whereby the vibration of said diaphragm determines the amount of gas passing out of said gas escape means, and means for supporting a flame at the outside end of said gas escape opening whereby when said combustible gas is ignited the acoustic output of said loudspeaker is increased.
3. In combination a loudspeaker having a diaphragm and means for vibrating said diaphragm responsive to electrical signals, a rear closure means for said loudspeaker comprising a box having an opening in one wall thereof the size of said diaphragm, means mounting said loudspeaker in said box with said diaphragm facing outwardly within said openings, a front closure means mounted on said box over said loudspeaker diaphragm, said front closure means having walls opposite said diaphragm which are spaced therefrom and substantially parallel thereto and defining therewith a modulating enclosure, a source of combustible gas, means for introducing said source of combustible gas at a location of said diaphragm displaced from the center thereof into said modulating chamber, and a gas escape opening through said enclosure member extending from the region thereof over the center of said diaphragm outwardly, whereby when said combustible gas escaping from said escape opening is ignited the output of said loudspeaker is increased.
